STRETCHER

Harry T. Anderson, New Philadelphia, and Edgar C. Davis, Dover, Ohio

Application October 24, 1933, Serial No. 695,012

7 Claims. (Cl. 5—82)

This invention relates to stretchers, and has for its object the provision of novel means whereby the disabled person or patient may be expeditiously placed on the stretcher without the application of force which will inconvenience the person or cause him agony due to the manipulations that are necessary to place him on the stretcher. As has been stated, the stretcher is intended for use in handling disabled persons, whether they have been sick or injured, and in further reference to such persons for convenience in description they will be referred to as "patients", which will comprehend all of the foregoing conditions.

It is an object of this invention to provide a stretcher having lengths of patient supporting fabric which are separable one from the other, by reason of their being movable independently one of the other transversely of a frame on which the fabric is mounted; means being provided in association with the fabric and the frame for retaining the lengths of fabric in certain positions of adjustment; means being also provided whereby lengths of fabric are supported by the aforesaid fastening means whereby a strong and durable sustaining web is provided.

It is a further object of this invention to provide a sectional frame, the sections of which may be adjusted with relation to one another, whereby one end of the frame may be swung or adjusted to positions at angles with relation to the other end of the frame, the said adjustment being attainable within the range of 180 degrees; means being provided for securing the sections in different degrees of adjustment in order that the patient may assume a natural sitting position and be supported, or that he may be supported in reclining positions at different angles, according to the desires of the attendant or patient.

It is furthermore an object of the invention to provide means whereby the side members or bars of a stretcher may be moved apart while the frame is being placed over a patient preparatory to the adjustment of the supporting fabric as it is placed under the patient, it being understood that means are provided for holding the side members against movement, except when certain securing devices are released to permit adjustments.

It is furthermore an object to provide telescopically arranged bars at the ends of the stretcher which connect the side members, the arrangement being such that a rigid rectangular frame results when the fastenings are applied

for holding the parts together, and the aforesaid securing parts are also associated with means at the ends of the fabric for supporting and tensioning the said fabric lengthwise.

It is a still further object of this invention to provide handles which are adjustable to positions parallel with the side members or at right angles thereto and said adjustment is afforded at positions between the aforesaid locations, it being understood that the said handles may act as feet or supports for the stretcher which will serve to hold it above the floor or ground in order that the stretcher may be expeditiously manipulated and the side members thereof grasped.

With the foregoing and other objects in view, the invention consists in the details of construction and in the arrangement and combination of parts to be hereinafter more fully set forth and claimed.

In describing the invention in detail, reference will be had to the accompanying drawing forming part of this application, wherein like characters denote corresponding parts in the several views, and in which—

Figure 1 illustrates a plan view of a stretcher embodying the invention;

Figure 2 illustrates a side elevation thereof with the handles adjusted to support the frame;

Figure 3 illustrates a sectional view through the side members approximately on the line 3—3 of Fig. 2;

Figure 4 illustrates a face view of the inner end of one of the sections of the side frame;

Figure 5 illustrates a plan view of a fragment of the stretcher at one corner, partly in section; and

Figure 6 illustrates a perspective view of a detail of means for connecting the fabric straps to the side members.

In the present embodiment of the invention, the sectional side members each consists of a tubular section 10 and 11 whose contiguous ends have serrated contacting surfaces as shown at 12, and a pivot 13 extends through the said ends, the said pivot being in the nature of a bolt having a fastening threaded thereon, the said fastening being here shown as in the nature of a wing nut 14.

The side members are, as heretofore stated, provided with a plurality of handles and, in the present embodiment of these handles, a boss 15 is provided for each handle and it may be secured to the side member by any appropriate mechanical fastening, or by the usual welding processes. The sections of the side members preferably con-

sist of tubular metal so that the bosses may be secured to them as desired. Each boss has a serrated face 16, the serrations of which are engaged by serrations 17 on the body 18 of the handle 19 and a threaded stud 20 on the boss extends through an aperture of the body of the handle and a threaded element 21 threaded on the stud holds the serrated surfaces of the boss and handle interlocked for retaining the handle at different positions of adjustment, to which reference has been made.

The sections of the side members each has at its outer end a handle 22 that may be secured in place in any desired manner, but for the purpose of illustrating one embodiment, the handle 22 is shown as having a shank 23 extending into the tubular section, the same being held in place by a cross pin 24. Each section of the side members at or near the end having the handle is provided with laterally extending bars 25 which telescope in a tube 26, it being understood that a bar from each side member at one end enters the tubular member, and the tubular member is slotted as at 27 for the purpose of receiving the hooked ends 28 of the rods 29. Each rod has a shank 30 passing through apertures of a side member. The shank is threaded as at 31 and it is engaged by a nut 32 which serves to hold the hooked end of the rod in the tubular member, the inner extremity of the hook being seated in an aperture of the bar 25. The hook furthermore engages a shoulder 25a at the end of the slot of the bar and this serves to limit the movement of the bar.

As shown in the drawing, the bottom panels 33 and 34 each has eyelets or apertures 35 in which members which in their physical embodiment may be in the nature of loops 36 are located, each set of loops embracing one of the rods 29. The loops are slidable on the rods as the panels are moved laterally of the frame when a patient is to be placed on the stretcher. As has been stated, the panels which form the bottom of the stretcher are separable one from the other transversely of the frame in order that a space between the panels may be created to permit the frame to be placed over the patient and the said panels adjusted under him so that the patient may be lifted with the manipulation of the stretcher. In order to accomplish the foregoing result, the panels are provided with securing and sustaining elements of novel construction. In the present embodiment of the invention, each panel is provided near its outer edge with a plurality of fabric straps 37. The inner end of each strap is secured to the under surface of the panel near its edge and the outer end of said strap is anchored to the adjacent side member, which side member has a plurality of pins 38 to which apertured ends of the straps are applied. These straps 37 serve to hold the panels against inward movement.

As a further means for holding the panels stretched and supported, straps of fabric of suitable length are associated with the respective panels as follows. One such strap identified by the numeral 39 is secured to the panel 34 and underlies the panel 33, the said strap being secured to the side member of the frame adjacent the panel 33, the said fastenings being the same as described as anchorages for the straps 37. Another such strap 40 alternating with the strap 39 is secured at one end to the panel 33 and it underlies the panel 34 acting as a support for the same and the said strap is secured to the side member adjacent the panel 34. The aforesaid straps 39

and 40 alternate in the manner stated, except that in the center or approximate center of the frame, two of the supporting or sustaining straps 41 are connected to both of the side frame members, for it is at this location that the greatest weight is usually present during the use of a stretcher. Of course the joints between these straps and the frame members are removable in order that the side frame members may be separated from each other or adjusted in applying the stretcher to the patient or vice versa. One of the sustaining straps 41 is secured to the panel 33 and extends under the panel 34, whereas the other such strap is secured to the panel 34 and extends under the panel 33 but, as stated, both ends of each strap are anchored to the side members of the frame.

In Figure 6 there is shown a snap fastening by which the fabric straps may be anchored or attached to the side members but this is a detail of construction which may be changed to suit particular requirements.

Instead of the loops 36, devices may be substituted therefor such as double ended snap hooks or other openable link members which will permit them to be detached from the rods without the necessity of removing the rods from the said side members or bars. Since devices of this type are well known, it is believed unnecessary to illustrate an example of a common type.

We claim:

1. A stretcher comprising a rectangular frame, supporting panels elongated longitudinally of the frame and separable one from the other at the centre of the frame, members connected to the ends of the panels, means connected to the ends of the frame for slidably supporting the members near the ends of the frame, and means connected to the panels and anchored to the frame for holding the panels in operative positions.

2. A stretcher comprising a rectangular frame, rods near each end of the frame, supporting panels extending longitudinally of the frame and terminating near the aforesaid rods, members anchored to the said panels near their ends and slidably engaging the aforesaid rods whereby the panels may be moved laterally in opposite directions, and elements attached to the said panels and detachably connected to the frame for holding the panels in operative positions.

3. A stretcher comprising a rectangular frame, rods connected to the frame near each end thereof, supporting panels extending longitudinally of the frame and terminating near the aforesaid rods, members anchored to the said panels near their ends and slidably engaging the aforesaid rods whereby the panels may be moved laterally in opposite directions, elements attached to each of the panels and extending under the other panel and projecting therebeyond, and means for detachably connecting the extended portions of the elements to one of the frame elements.

4. A stretcher comprising a rectangular frame, rods connected to the frame near each end thereof, supporting panels extending longitudinally of the frame and terminating near the aforesaid rods, members anchored to the said panels near their ends and slidably engaging the aforesaid rods whereby the panels may be moved laterally in opposite directions, elements attached to the respective panels and projecting under the opposite panel and extending therebeyond, and means for detachably connecting the projected portions of the elements to the frame.

5. A stretcher comprising a rectangular frame,

- rods connected to the frame near each end thereof, supporting panels extending longitudinally of the frame and terminating near the aforesaid rods, members anchored to the said panels near 5 their ends and slidably engaging the aforesaid rods whereby the panels may be moved laterally in opposite directions, elements attached to the respective panels and projecting at the edges thereof, and means for detachably securing the 10 projected portions of the elements to the frame.
6. In a stretcher, a frame comprising sectional side members, means for pivotally connecting the inner ends of the members on each side together, means for adjustably holding the sections at 15 different positions of adjustment, inwardly extending elements on each of the sections of the side members near their outer ends, a tubular member in which they telescope, rods having hooked inner ends extending into the tubular member at each end of the frame and engaging the transversely disposed 15 members, each of the rods having a shank extending through a side member, means for securing the shank to the said side member, patient supporting panels encompassed by the frame, and means secured to the panels near 20 their ends and slidable on the rods for supporting the said panels.
7. In a stretcher, a frame comprising sectional side members, means for pivotally connecting the inner ends of the members on each side together, means for adjustably holding the sections at different positions of adjustment, a handle on the outer end of each section, a handle on the side of each section of the side member, means for holding the handle on the side of the section parallel with the side member or at angles with 10 relation thereto, inwardly extending elements on each of the sections of the side members near their outer ends, a tubular member in which they telescope, rods having hooked inner ends extending into the tubular member at each end of the frame and engaging the transversely disposed 15 members, each of the rods having a shank extending through a side member, means for securing the shank to the said side member, patient supporting panels encompassed by the frame, and means secured to the panels near 20 their ends and slidable on the rods for supporting the said panels.
